Miriam Cohen, Forest Hills, N. Y.

Application August 17, 1943, Serial No. 499,027

4 Claims. (Cl. 24—6)

The present invention relates to holders, and more particularly to holders for the stems of flowers, corsages or similar objects which may be secured, if desired, to the wearing apparel or hair of a wearer.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations, and improvements herein shown and described.

The accompanying drawing, referred to herein and constituting a part hereof, illustrates one embodiment of the invention, and together with the description, serves to explain the principles of the invention.

It is an object of the present invention to provide a simple and efficient holding device for the stems of flowers, corsages, or other objects and one which may be utilized to secure such objects to the wearing apparel or hair of the wearer. Another object is to provide such an article holder in which the article, such as a flower stem, may be placed with a minimum of trouble and complication, and which securely holds a stem once placed therein. Still another object is the provision of a stem holder which is relatively simple and economical to make. The invention further provides an unobtrusive holder for stems and other objects after affixing to the apparel or hair of a wearer.

Of the drawing:

Fig. 1 is a perspective view of a typical and illustrative embodiment of the present invention;

Fig. 2 is a perspective view of the embodiment of the invention shown in Fig. 1 showing a flower stem in place and secured on the stem holder; and

Fig. 3 is a sectional view taken along line 3—3 of Fig. 2, the arrows of reference numerals 3—3 being tilted to indicate less than a 90° change in viewpoint.

Referring now to the illustrative embodiment of the present invention shown by way of example in the accompanying drawing, the stem holder may comprise a shaft member 10 made of wire or other suitably stiff material. Adjacent the upper end of the shaft 10 there is provided a closed loop support 11 horizontally disposed against shaft member 10 and firmly secured

thereto. The support 11 is likewise made of wire or other suitably stiff material.

A closed loop member 12 is provided made of wire or material giving a similar rigidity and is 5 passed through the loop support 11 on either side of the shaft member 10. The rigid loop 12 is bent at its upper portion 13 so that its lower loop portion 14 may swing somewhat outwardly of the shaft 10.

10 A closed elastic loop 15, such as a rubber band, is linked with rigid loop member 12. This may be done by closing the rigid material of loop member 12 around a segment of elastic loop 15, or by closing the elastic material around a segment of loop member 12, to form the loop 15.

There is provided adjacent the lower end of shaft member 10 a cross support 16 which is preferably in the form of a downwardly turned V. An elongated pin member 17 is firmly secured to the shaft member 10 at its upper end as at 18. The lower end of shaft member 10 is formed in a hook 19 in which the lower end of pin 17 may be engaged when a stem holder is in place on the wearing apparel or hair of a wearer.

20 25 As may be seen in Figs. 2 and 3, a stem 21 may be passed through the rigid loop 12 and downwardly adjacent to and substantially parallel with the shaft member 10. The closed elastic loop 15 may then be stretched and hooked over

30 35 the ends of cross support 16 which serves as an anchor for said stretched elastic loop 15, thus providing a loop 20 at the front of the stem holder through which the lower end of the stem may be passed. The stem is thus securely held in place against shaft member 10 by the pressure of closed rigid loop 12 and the loop portion 20 of closed elastic loop 15.

The invention in its broader aspects is not limited to the specific mechanisms shown and described but departures may be made therefrom within the scope of the accompanying claims without departing from the principles of the invention and without sacrificing its chief advantages.

45 What I claim is:

1. A holder for the stem of a flower or like object including in combination a shaft member, a closed rigid loop pivotally mounted on said shaft member through which loop the stem is passed, and resilient means connected to said loop and extensible between said loop and an anchor on said shaft member to apply a resilient bias of said loop against said shaft member whereby to resiliently secure said stem between said loop and said shaft member.

2. A holder for the stem of a flower or like object including in combination a shaft member, a closed rigid loop slidably mounted on said shaft member and held against axial movement, through which loop the stem is passed, and elastic means connected to said loop and extensible between said loop and an anchor on said shaft member to apply a resilient bias of said loop against said shaft member said anchor being rigidly mounted on said shaft member at a point spaced apart from said loop, whereby to resiliently secure said stem between said loop and said shaft member.

3. A holder for the stem of a flower or like object including in combination a shaft member, a closed rigid loop pivotally mounted on said shaft member through which loop the stem is passed, resilient means connected to said loop and extensible between said loop and an anchor

on said shaft member to apply a resilient bias of said loop against said shaft member whereby to resiliently secure said stem between said loop and said shaft member and means carried by said shaft member for securing the holder in desired position.

4. A stem holder comprising, in combination, a shaft member, a rigid support loop secured to said member, a rigid loop slidably carried by said support loop, a cross support secured to said shaft member spaced apart from said loops, and a closed elastic loop secured to the slidably carried rigid loop and extensible to and around said cross support, whereby a stem adjacent said shaft member may be passed through said slidably carried rigid loop and held against said shaft member by the resiliency of said loop of elastic in extended position.

MEYER COHEN.
